(57) **CLAIM**

The ornamental design for an assist plug, as shown and described.

DESCRIPTION

FIG. 1 is a perspective view of an assist plug from the top, front and left side according to the present design;
FIG. 2 is a perspective view thereof from top, rear and right side;

FIG. 3 is a front elevational view thereof;

FIG. 4 is a rear elevational view thereof;

FIG. 5 is a right side elevational view thereof;

FIG. 6 is a top plan view thereof;

FIG. 7 is a left side elevational view thereof;

FIG. 8 is a bottom plan view thereof;

FIG. 9 is a perspective view showing a second embodiment of an assist plug from the top, front and left side according to the present design;

FIG. 10 is a perspective view thereof from top, rear and right side;

FIG. 11 is a front elevational view thereof;

FIG. 12 is a rear elevational view thereof;

FIG. 13 is a right side elevational view thereof;

FIG. 14 is a top plan view thereof;

FIG. 15 is a left side elevational view thereof;

FIG. 16 is a bottom plan view thereof;

FIG. 17 is a perspective view showing a third embodiment of an assist plug from the top, front and left side according to the present design;

FIG. 18 is a perspective view thereof from top, rear and right side;

FIG. 19 is a front elevational view thereof;

FIG. 20 is a rear elevational view thereof;

FIG. 21 is a right side elevational view thereof;

FIG. 22 is a top plan view thereof;

FIG. 23 is a left side elevational view thereof;

FIG. 24 is a bottom plan view thereof;

FIG. 25 is a perspective view showing a fourth embodiment of an assist plug from the top, front and left side according to the present design;

FIG. 26 is a perspective view thereof from top, rear and right side;

FIG. 27 is a front elevational view thereof;

FIG. 28 is a rear elevational view thereof;

FIG. 29 is a right side elevational view thereof;

FIG. 30 is a top plan view thereof;

FIG. 31 is a left side elevational view thereof; and,

FIG. 32 is a bottom plan view thereof.
